UNITED STATES PATENT OFFICE

ERNST RUESS, OF MUNICH, GERMANY

CARRYING BODY FOR RIGID AIRSHIPS

Application filed October 2, 1928, Serial No. 309,724, and in Germany June 14, 1926.

The carrying bodies for rigid airships have hitherto consisted exclusively of a skeleton of aluminium or wood, stayed in a suitable manner and having a multi-cornered cross section.

It has been found that these carrying bodies for airships cause extraordinarily high expenses at the erection of the airship, as this erection requires much time and a great number of workmen. The skeletons of aluminium or wood do not possess the necessary resistance, which cannot be obtained even by the cleverest possible stay work. This inconvenience is specially disagreeable at hard landings or when the airship is landing with a strong shock, whereby the hull of the airship is generally distorted or some of the members of the skeleton are bent inward and the ship's hull is considerably damaged. It even happens sometimes that the hull is wrecked completely.

The commonly used airship bodies possess further very little elasticity, this being specially unfavourable in whirlwinds.

On the commonly used airship bodies the driving engines can be mounted only in the lower portion of the body, wherefrom results an unfavourable stress on the body of the airship, a high engine efficiency being further required as the tractive effect does not act parallel to the axis of the airship.

The hitherto used airship bodies are further unsuitable for the arrangement of supporting planes designed to make the airship capable to operate like an aeroplane, i. e. to rapidly ascend or descend. The commonly used airship bodies do not withstand the strong stresses of the supporting planes so that it has not yet been possible to build a combined airship-aeroplane.

This invention has for its object to create an airship body which avoids all the inconveniences mentioned above by being made of felloe-like rims which may be constructed as single felloe or as double felloe and which are

connected to each other in a suitable manner.

An airship body constructed in accordance with the invention is shown, by way of example, in the accompanying drawing in

Fig. 1 in longitudinal section.

Fig. 2 shows a portion of the airship body in longitudinal section.

Fig. 3 is a cross section on line 3—3 of Fig. 1, on an enlarged scale.

The carrying body is of torpedo-shape; it might however be of any cylindrical or other shape. The skeleton of the carrying body is composed of felloe-like hoops, rings or rims *a*, *b*, i. e., of a particular channeled (C) cross-section and of suitable diameter, spaced, for instance, 5 meters apart and connected with each other in a suitable manner. The bow *c* and the stern *d* of the carrying body may consist of hoods placed on the body. These felloe-like rims shown on the drawing are double felloes, each element consisting of an inner felloe *a* and of an outer felloe *b*. The two felloes are connected with each other by stays and by longitudinal members.

Fig. 2 shows the longitudinal staying by means of girder members *e* fixed on inner retaining rings *f* of the double felloes *a*, *b*.

Fig. 3 shows two different stayings *g* and *h* in the annular space of the double felloe. The inner felloes *a* might be further stayed spoke-like.

The free space between two adjacent or several adjacent double felloes serves for accommodating the gas cells.

The outer skin is fixed on the outer felloes *b*, eventually with utilization of the longitudinal members *e*. Instead of the double felloes single felloes might be used as mentioned.

The new carrying body increases the resistance of the airship, enables the uniform distribution of the driving engines over the entire circumference of the airship, whereby prejudicial tensile stresses are avoided, and permits further of arranging supporting

planes on the airship, as the carrying body is sufficiently strong to intercept the great stresses.

The staying and connecting of the felloes ⁵ *a, b* only in the annular space between the same presents further the advantage that almost the complete hollow space of the carrying body may be utilized for accommodating gas cells.

10 I claim:—

1. A frame for rigid airships embodying connected outer and inner circular frame members of channeled cross-section arranged in pairs, the frame members of each pair being ¹⁵ concentrically disposed and one member of each pair having the open side of its channel facing outwardly and the other member of each pair having the open side of its channel facing inwardly.

20 2. A frame for rigid airships embodying connected circular frame members of cross-sectionally channeled form and arranged in pairs, the members of each pair being concentrically disposed and having their closed ²⁵ sides facing each other.

3. A frame for rigid airships embodying connected circular frame members of cross-sectionally channeled form and arranged in pairs, the members of each pair being ³⁰ concentrically disposed and having their closed sides facing each other, transverse bracing means between and connecting the closed sides of each pair of frame members, and longitudinal bracing means between the respective pairs of frame members and connecting the transverse bracing means of adjacent frame members.

4. A frame for rigid airships embodying connected circular frame members of cross-sectionally channeled form and arranged in pairs, the members of each pair being concentrically disposed and having their closed sides facing each other, retaining rings between the closed sides of each pair of frame members, longitudinal braces connecting adjacent pairs of frame members and fitted in said retaining rings, and truss braces connecting frame members and retaining rings of each pair of frame members and also connecting the aforesaid parts of adjacent pairs of frame members together.

5. A frame for an airship of rigid type embodying inner and outer sets of circular frame members of channeled cross-section and arranged in pairs, the frame members of each pair being concentrically disposed and having the closed sides of their channels facing each other and spaced apart, retaining rings in the spaces between the closed sides ⁵⁵ of the frame members, inner and outer longitudinal stays respectively uniting inner and outer frame members of adjacent pairs of frame members, and stays in the spaces between and connecting the frame members ⁶⁰ of the pair of frame members and extending

longitudinally between adjacent pairs of frame members between the said inner and outer longitudinal stays.

6. A frame for rigid airships comprising outer and inner circular rings disposed in pairs, the rings of each pair being concentrically arranged and each ring being cross-sectionally of channeled form, stays between the rings of each pair, retaining rings between the frame rings of each pair, and longitudinal girders connecting adjacent frame rings and fitted in said retaining rings.

In testimony whereof I affix my signature.
ERNST RUESS.
